Primary Examiner — Kevin K Rudzinski*Assistant Examiner* — Kathleen L Jones(74) *Attorney, Agent, or Firm* — Law Office of Jeff Williams; J. Oliver Williams(57) **CLAIM**

The ornamental design for an orbital gear replacement insert, as shown and described.

DESCRIPTION

FIG. 1 is a front perspective view of an orbital gear replacement insert according to the present application.

FIG. 2 is a front view of the orbital gear replacement insert of FIG. 1.

FIG. 3 is a rear view of the orbital gear replacement insert of FIG. 1.

FIG. 4 is a right view of the orbital gear replacement insert of FIG. 1.

FIG. 5 is a left view of the orbital gear replacement insert of FIG. 1.

FIG. 6 is a top view of the orbital gear replacement insert of FIG. 1; and,

FIG. 7 is a bottom view of the orbital gear replacement insert of FIG. 1.

1 Claim, 5 Drawing Sheets(56)
